(57) **CLAIM**

The ornamental design for a smart projector, as shown and described.

DESCRIPTION

FIG. 1 is a front elevation view of a smart projector showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof; and,

FIG. 8 is a detail view of the portion of FIG. 7 encircled in dot-dash lines.

The broken lines depict portions of the article that form no part of the claimed design.

The dot-dash lines in FIGS. 7 and 8 point to and encircle a detail portion of the figures and form no part of the claimed design.
